UNITED STATES PATENT OFFICE.

HARRY NORTHWOOD, OF WHEELING, WEST VIRGINIA.

LIGHTING-FIXTURE.

1,247,445.

Specification of Letters Patent. Patented Nov. 20, 1917.

Application filed June 25, 1917. Serial No. 176,655.

To all whom it may concern:

Be it known that I, HARRY NORTHWOOD, a citizen of the United States of America, and resident of Wheeling, county of Ohio, 5 and State of West Virginia, have invented certain new and useful Improvements in Lighting-Fixtures, of which the following is a specification.

This invention relates broadly to lighting fixtures, and more specifically to an electric lighting unit of that type which embodies a suspended light-shielding bowl.

The primary object of the invention is to provide an electric light fixture of the semi-indirect type, wherein the light-diffusing bowl is shielded in such manner that the collection of dust therein is largely prevented.

A further object is to provide, in a device of the character mentioned, a mouth-closing shield for the light-diffusing bowl which is of such form and character that it not only does not detract from the appearance of the fixture, but also does not appreciably impair the lighting efficiency of 25 such devices.

A still further object of the invention is to provide a lighting device which includes a light-diffusing bowl and a dust shield adapted to be supported by or suspended 30 from a socket cover mounted upon an ordinary suspended electric-light socket, and which involves a simple construction adapted to be readily installed by unskilled persons, and as readily removed when occasion 35 requires.

With these and other objects in view, the invention resides in the features of construction, arrangement of parts and combinations of elements which will hereinafter 40 be fully described, reference being had to the accompanying drawing, the single figure of which illustrates a central vertical section of the invention.

In said drawing, 1 indicates a light-in-45 closing diffusing bowl, and 2 a shade or reflector, said parts being of a common or any appropriate form. Said parts are supported by a socket-cover which is preferably of the character disclosed in Patent No. 50 1,225,049, issued to me on the 8th day of May, 1917, but it will be understood that I do not confine myself to the use of the socket cover of said patent. Said preferred form of socket-cover illustrated in the draw-55 ings consists of a cylindrical shell or casing 3 and a telescoping dome-member 4, said

casing having an inturned flange 5 at its upper end for resting upon a shoulder 6 formed on said dome-member, and having a lower flared end, or skirt 7 whereby is 60 formed an annular shoulder 8. Said socket cover is designed for seating upon a light-socket in embracing relation to a socket suspension cord or the like.

The diffusing bowl is suitably suspended 65 from the lower part or skirt 7 of the casing 3, as by means of chains 9. Disposed in embracing relation to said casing and resting upon the shoulder 8 thereof is the neck portion of the reflector 2 which is of wide flaring form and which is preferably composed of translucent glass. A ring-like apron 10 of metal loosely encircles the casing and has its lower edge resting upon the top of said reflector for concealing the neck portion 70 of the latter, thereby to enhance the appearance of the fixture.

Interposed between the reflector 2 and the bowl 1 is a plain transparent glass shield 11 of widely flared bell-like form, the 75 lower edge of which is designed to rest upon and embrace the open upper end, or mouth, of said bowl for excluding dust from the latter. Said shield has its upper portion or neck loosely embracing the skirt 7 of the 80 casing 3 so that it is vertically movable with respect to the latter to compensate for slight variations in the length of the chains 9 employed for supporting the bowl. In this connection it will be noted that the shield 85 is supported by the bowl rather than by the socket-cover.

The dome-member 4 is preferably of the split form disclosed in my said Patent No. 1,225,049, having a radial incision in one 90 side thereof for facilitating introduction of the socket-suspension element.

In mounting the fixture, the apron 10, reflector 2 and shield 11 are separately and in the order named slipped upward over the light socket to an out-of-the-way position on the suspension cord above said socket. Then, the casing 3 to which the bowl 1 has 100 previously been attached by means of the chains 9 is in like manner slipped upward over the socket to a position on the cord a suitable distance above said socket. The dome-member 4 is then applied in encircling relation to the cord at a point between the socket and the parts previously applied, as aforesaid, after which said dome-member 105 is thrust upward or telescoped within the 110

casing to a position wherein its shoulder 6 seats against the flange 5 of said casing. The casing, dome-member and suspended bowl are then lowered to permit said dome-member to seat upon the light-socket, and the lamp is then introduced in the latter. And, finally, the shield, reflector and apron are successively lowered to their respective seating positions.

10 It will be apparent from the foregoing that the fixture involves a minimum number of compactly arranged parts of relatively simple and inexpensive construction which may be readily installed in assembled relation and dismounted without the exercise of other skill than that possessed by the average person.

15 While I prefer to employ a reflector as a part of the fixture, it will be obvious that the reflector might be omitted if desired.

20 What is claimed is—

25 1. In a lighting fixture, the combination with a socket cover, of a diffusing bowl, means suspending said bowl from said cover, and a glass shield fitted in vertically adjustable embracing relation to said cover above the upper end of said suspending means and inclosing the latter, said shield being supported by said bowl and closing the mouth 30 of the same.

35 2. In a lighting fixture, the combination with a shouldered socket cover, of a reflector supported by the shoulder of said cover, a diffusing bowl, chains suspending said bowl from said cover, and a glass shield interposed between said reflector and said bowl, said shield embracing said cover below said shoulder and having its lower edge disposed in closing relation to the mouth of said 40 bowl.

45 3. In a lighting fixture, the combination with a socket cover, of a diffusing bowl, chains suspending said bowl from said cover, and a glass shield embracing said cover and resting upon said bowl in closing relation to the mouth of the latter, said shield be-

ing vertically adjustable to compensate for slightly varying lengths of bowl-supporting chains.

4. A lighting fixture comprising a socket cover having a flared lower end whereby is formed an annular external shoulder, a light-diffusing bowl suspended from said flared end, a reflector having a neck portion embracing said cover and seated upon said shoulder, said reflector being supported in overhanging relation to said bowl, and a glass shield interposed between said reflector and said bowl, said shield being disposed in embracing relation to said flared end of the cover and having its lower edge positioned in mouth-closing relation to said bowl.

5. A lighting fixture comprising a socket cover having a flared lower end whereby is formed an annular external shoulder, a light-diffusing bowl suspended from said flared end, a reflector having a neck portion embracing said cover and seated upon said shoulder, said reflector being supported in overhanging relation to said bowl, and a glass shield interposed between said reflector and said bowl, said shield embracing and being vertically movable with respect to said cover and resting upon said bowl in mouth-closing relation to the latter.

6. A lighting fixture comprising a socket cover, a reflector embracing and supported by said cover, a light-diffusing bowl, means suspending said bowl from said cover, and a bell-like glass shield encircling said cover below said reflector and inclosing said suspending means, said shield being disposed in closing relation to the mouth of said bowl.

85 In testimony whereof, I affix my signature in presence of two subscribing witnesses.

HARRY NORTHWOOD.
